UNITED STATES PATENT OFFICE.

MAGGIE PUTNEY, OF COLEMAN, TEXAS.

DRESSMAKER'S SKIRT-MEASURING DEVICE.

No. 910,084.

Specification of Letters Patent.

Patented Jan. 19, 1909.

Application filed June 10, 1908. Serial No. 437,774.

To all whom it may concern:

Be it known that I, MAGGIE PUTNEY, a citizen of the United States, residing at Coleman, in the county of Coleman and State of Texas, have invented new and useful Improvements in Dressmakers' Skirt-Measuring Devices, of which the following is a specification.

This invention relates to a measuring device intended primarily for use by dressmakers and tailors to accurately obtain the proper measure of skirts and in locating the desired point where tucks, ruffles, and trimmings are to be placed.

The invention has for one of its objects the provision of a measuring device of this character which is of comparatively simple and inexpensive construction, convenient and reliable in use, and readily manipulated for obtaining the various measurements.

Another object of the invention is the employment of a stand or base on which the person to be fitted stands and which is provided with a swinging arm to which the lower end of a tape is applied, the opposite end of the tape being attached to a chain or equivalent means applied to the waist of the person and on which the tape can be worked around, in accordance with the movement of the arm on the stand or base, so that measurements can be taken at every point around the skirt.

With these objects in view and others, as will appear as the description proceeds, the invention comprises the various novel features of construction and arrangement of parts which will be more fully described hereinafter and set forth with particularity in the appended claims.

In the accompanying drawing, which illustrates one embodiment of the invention, Figure 1 is a front view of the device illustrating the application thereof. Fig. 2 is a plan view of the base. Fig. 3 is a central vertical section thereof. Fig. 4 is a perspective view of the belt or chain to which the upper end of the measuring tape is attached. Fig. 5 is a plan view of the swinging arm on the base to which the lower end of the measuring tape is attached.

Similar reference characters are employed to designate corresponding parts throughout the views.

Referring to the drawing, A designates a stand that consists of a tripod formed of a plate 1 and feet 2 and on which rests a pedes-

tal 3, and supported on the upper end of the pedestal is a top 4 on which the person to be fitted stands. The tripod, pedestal, and top 4 are removably connected together by means of a bolt 5 passing through the top, pedestal, and plate 1, as shown in Fig. 3, the bolt enabling the base to be readily taken apart for conveniently packing the same for shipment. The lower end of the pedestal has a circular portion 6 on which turns an arm 7 that has a circular head or ring 8 into which the lower end 6 of the pedestal fits, the arm being held from vertical movement by a shoulder 9 at the top of the ring and the plate 1 of the tripod at the bottom of the ring. The arm 7 has a handle extension 10 connected with the outer extremity of the arm by a hinge 11, whereby the said handle extension can be folded backwardly under the top 4 when the base is not in use so as to be out of the way and also adapt the stand to be used as a stool. On the bottom of the top 4 is a drawer 12 for holding the tape measure and belt member, chalk, pins, thread, and the like.

The tape measure B is of that type consisting of a casing 13 into which the tape is retrieved by a spring when the free end of the tape is released. The tape has a hook 14 for engaging in any one of a plurality of loops or eyes 15 in the arm 7, while the casing 13 of the tape is attached to the belt element C of the device. In the present instance, this device is in the form of a chain of such length as to fit any size waist and is equipped with a hook 16 for engaging any link of the opposite end of the chain for fastening the latter around the waist, there being metal or other knobs 17 on the extremities of the chains which serve as stops for preventing the slide 18 from dropping off when the chain is removed from the body. This slide 18 has a hook or eye 19 whereby the casing 13 of the tape measure is attached to the belt element C.

In measuring the skirt, the person to be fitted stands on the base A at about the center thereof and the tape-attaching means or element C is applied to the waist and the tape B pulled out of the casing a sufficient distance from the free end to be hooked on the arm 7, the tape thus passing from the waist of the skirt to a point below the top 4. The divisions of the tape begin at a point coincident with the top of the part 4 which is equivalent to the floor line so that the dis-

2
tance between the latter and the bottom of the skirt will be the height of the skirt off the floor. In taking the measurements, the arm 7 will be vertically under the point 5 where the tape is attached to the waist element C, and the pin or other marker is inserted in the skirt at the desired height and to take the next measurement, the arm is moved to the right or left and the slide 18 10 shifted in a corresponding direction to permit of a second measurement and in this manner, the successive measurements are taken.

From the foregoing description, taken in 15 connection with the accompanying drawing, the advantages of the construction and of the method of operation will be readily apparent to those skilled in the art to which the invention appertains, and while I have 20 described the principle of operation of the invention, together with the device which I now consider to be the best embodiment thereof, I desire to have it understood that the device shown is merely illustrative, and 25 that such changes may be made when desired as are within the scope of the claims appended hereto.

Having thus described the invention, what I claim is:—
30 1. The combination of a base, a member

mounted thereto to swing in a horizontal plane, a measuring tape attached at one end to the member, a waist-encircling element, and means for adjustably connecting the tape measure to the said element. 35

2. In a device of the class described, the combination of a base or stand, a swinging arm mounted thereon at a point below the top of the stand, means for adjustably connecting a tape measure to the arm, a waist- 40 encircling element, a slide on the said element, and means for connecting the tape measure thereto.

3. In a device of the class described, the combination of a waist-encircling element, 45 a slide freely movable thereon, a measuring device including a self-winding tape and a casing therefor, means for securing the casing to the slide, a stand having a movable member adapted to be moved together with 50 the slide for taking measurements at different points, and means for attaching the tape to the member.

In testimony whereof I affix my signature in presence of two witnesses.

MAGGIE PUTNEY.
